US0D1063101S

(12) **United States Design Patent** (10) **Patent No.:** **US D1,063,101 S**
(45) **Date of Patent:** **** Feb. 18, 2025**

(54) **LIQUID SAMPLE COLLECTOR**

(71) Applicant: **Hangzhou Biotest Biotech Co., LTD.**,
Hangzhou (CN)

(72) Inventors: **Shujiang Wu**, Hangzhou (CN);
Junsheng Wu, Hangzhou (CN); **Yang Wang**, Hangzhou (CN); **Liang Hong**, Hangzhou (CN)

(73) Assignee: **HANGZHOU BIOTEST BIOTECH CO., LTD.**, Hangzhou (CN)

(**) Term: **15 Years**

(21) Appl. No.: **29/884,301**

(22) Filed: **Feb. 9, 2023**

(30) **Foreign Application Priority Data**

Dec. 8, 2022 (CN) 202230824957.3

(51) **LOC (15) Cl.** **24-02**

(52) **U.S. Cl.**

USPC **D24/216**

(57) **CLAIM**

The ornamental design for a liquid sample collector as shown and described.

DESCRIPTION

FIG. 1 is a front top perspective view of the liquid sample collector showing our new design;

FIG. 2 is a front bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the liquid sample collector that form no part of the claimed design.

1 Claim, 8 Drawing Sheets
